EAVES-TROUGH HANGER

Oren E. Sheets, 112 E. Jackson St., Columbia City, Ind.

Filed July 30, 1958, Ser. No. 752,025

6 Claims. (Cl. 248—48.2)

The present invention relates to an eaves-trough hanger, and more particularly to a hanger to which a section of eaves-trough may be easily removably attached.

Customarily, troughs or gutters which rim the eaves of a building roof carry away the water which drains off the roof to suitably located downspouts. These troughs are ordinarily permanently affixed to the eaves by means of long spike nails and ferrules, these nails and ferrules being passed through one flange of the trough and into a part of the eave or roof structure.

When it becomes necessary to replace the trough, it is necessary first to pull the spikes. This is a major operation, since the nails are usually rusted and extremely difficult to pull, usually resulting in considerable damage to the trough itself.

With a trough mounted by means of spike nails, it is not feasible to remove the trough for purposes of servicing or painting. Instead, it is necessary to gain access to the trough by means of a ladder or the roof itself, both being attended with inconvenience and some danger of a worker accidentally falling.

The present invention differs primarily in the respect that it provides a device for hanging eaves-troughs or gutters in a more facile and economical manner, the trough after so mounted being easily demounted for painting or other servicing.

It is therefore an object of this invention to provide an eaves-trough hanger whereby an eaves-trough may be hung in a more facile and economical manner.

It is another object of this invention to provide an eaves-trough hanger which is capable of mounting detachably an eaves-trough in supported position.

Other objects will become apparent as the description proceeds.

To the accomplishment of the above and related objects, my invention may be embodied in the forms illustrated in the accompanying drawings, attention being called to the fact, however, that the drawings are illustrative only, and that specific change may be made in the specific constructions illustrated and described, so long as the scope of the appended claims is not violated.

In the drawings:

Fig. 1 is a side elevation of one embodiment of this invention shown as supporting a conventional eaves-trough in place;

Fig. 2 is a top plan view of Fig. 1 and shows a short length of eaves-trough as being mounted in place;

Fig. 3 is a rear view thereof;

Fig. 4 is an illustration of the retainer or lock shown in Figs. 1 and 2; and

Fig. 5 is a sectional illustration taken substantially along section line 5—5 of Fig. 1.

Referring to the drawings, the bracket or hanger of this invention comprises an elongated, substantially flat strap metal member 10 formed with a series of bends according to the configuration of Fig. 1. This member 10 has two principal parts, a leg 12 and an arm 14. The

leg 12 is substantially straight and elongated, and carries on its lower end an inwardly extending foot or flange 16 which is bent at substantially right angles to the leg 12. The leg may be formed with a reinforcing rib 18, as shown more clearly in Fig. 2, which is pierced at spaced intervals to provide a plurality of apertures 20. These apertures, as shown in Fig. 1, are adapted to receive nails, screws or the like 22 which are driven into a suitable facing or supporting board, as indicated by the numeral 24. This board 24 may constitute the eave of a roof.

The arm 14 is uniquely shaped as shown in Fig. 1 and extends forwardly to terminate in a downwardly bent flange 26. The portion of the arm intermediate the flange 26 and the leg 12 is preferably provided with a reinforcing rib 28 extending lengthwise of the arm. The upper end of the leg 12 and the left-hand end of the arm 14 are bent, as shown in Fig. 1, into the shape of an inverted U, the sides 30 and 32 of this U-shaped portion being compressed or squeezed together so as to provide a very narrow, slot-like space 34. The side 30, while it extends substantially parallel to the leg 12 for a short distance, gradually curves downwardly and outwardly until it straightens and merges into the arm 14 proper. As will appear from the following description, this slot-like space 34 between the leg 12 and the arm 14 serves a most useful purpose.

A lock or retainer 36 is suitably fastened to the outer end of the arm 14 and provides a means for anchoring or securing the hanger to an eaves-trough. This particular eaves-trough is shown in dashed lines in Fig. 1 and is identified by the reference numeral 38. This design of trough is conventional, having a flat rear wall 40, a flat bottom 42, an S-curved front wall 44, and a rearwardly extending flange 46 on the upper end of the front wall 44. As is shown in the drawings, the upper marginal edge of the rear wall 40 snugly fits into the slot 34, to be thereby held in place. The flange 16 on the lower extremity of the leg 12 receives the rear portion of the trough bottom 42, while the upper portion of the front wall 44 nests against the arm 14 and the depending flange 26. The retainer 36 is shown alone in Fig. 4 and preferably is fabricated of stiff, steel wire to the shape which corresponds to the capital letter Z. The upper arm or bar of this retainer is bent into the shape of a hook or stirrup 48. The remaining arm or bar 50 is bent downwardly slightly so as to provide a short shaft-like portion 52. This shaft portion 52 is received by an opening 54 in the outer end of the arm 14, the retainer arm 50 being on the underside of the arm 14 and the remaining portions 48 and 51 of the retainer being disposed on the upper side of the arm. As shown in Fig. 2, the hook or stirrup 48 embraces the trough flange 46 so as to secure the front of the trough against downward movement. The retainer arm 50 also passes beneath the trough flange 46 to engage and vertically support the trough. The retainer 36 may be easily detached from the trough by swinging it counterclockwise about the shaft portion 52, as viewed in Fig. 2. This withdraws both the hook 48 as well as the arm 50 from the trough flange 46.

In order to retain or lock the retainer 36 in the position shown in Fig. 2, a dimple or abutment 56 is formed on the top side of the arm 14 at a point immediately adjacent to the aperture 54. This abutment 56 is so positioned as to engage the intermediate portion 51 of the retainer 36 when the latter is in the illustrated locked position and to restrain or prevent thereby the retainer from swinging counterclockwise out of engagement with the trough flange 46.

In use, the bracket or hanger 10 without the trough 38 secured thereto is fastened to a suitable eave-board

24 by means of nails or screws 22. In this fastening, the hanger is positioned upright with the flange 16 at the bottom and the arm 14 extending outwardly from the eave 24. The retainer 36 is swung counterclockwise from the position shown in Fig. 2 until the mid-portion thereof snaps over the abutment 56. The eaves-trough 38 now is inserted into the hanger, with the upper marginal edge of the rear side 40 fitting into the slot 34. The flange 16 engages the bottom 42 of the trough, while the upper front trough portion nests between the arm 14 and the depending flange 26. As the final step in completing the attachment of the trough to the hanger, the retainer 36 is swung clockwise, as viewed in Fig. 2, until the hook 48 passes over and embraces the trough flange 46. The abutment 56 retains this hook 48 in engagement with the trough flange 46.

Detachment of the trough from the hanger is accomplished by merely removing the retainer 36 from the trough flange 46 and thereafter withdrawing the trough from the hanger. Any of these operations of attachment or detachment may be accomplished in a matter of seconds.

The shaft portion 52 of the retainer is only slightly longer than the thickness of the arm 14, so that the bar 50 in combination with the retainer mid-portion 51 loosely embraces the arm and thereby holds the assembly together. The dimple 56 is raised sufficiently so that when the mid-portion 51 is passed thereover it is sprung apart from the bar 50. This causes the retainer to snap into place on either side of the dimple and prevents accidental disengagement of the hook 48 from the trough flange when the mid-portion is positioned as shown in Fig. 2.

While only a single hanger 10 has been illustrated and described, it will be obvious to a person skilled in the art that a plurality of such hangers would normally be used in supporting a length of eaves-trough, the spacing between hangers 10 being, for example, two to four feet. Different spacings may be used. In mounting a long length of eaves-trough, the hangers 10 are first nailed in position along a previously drawn line, which provides the necessary fall in the eaves-trough. One person may thereupon lift a length of eaves-trough and snap it into each of the brackets 10 until the attachment has been completed for all of the brackets.

From the foregoing, it will be apparent that this invention permits a length of eaves-trough or gutter to be installed by one worker in contrast to the prior art arrangements which require, in almost every instance, two men to do the installing. Further, the individual hangers 10 may be fastened to an eave-board 24 along a drawn line which provides the desired fall in the gutter, thereby providing a facile method of achieving proper alignment.

The arm 14 is provided with an upwardly displaced reinforcing rib 28 which, in addition to strengthening the arm 14, also provides lateral drainage of any water into the gutter instead of toward the front or rear thereof.

While the retainer 36 has been described as conforming substantially to the shape of the letter Z, it will be obvious to a person skilled in the art that this shape may be changed without departing from the spirit and scope of this invention so long as the scope of the appended claims is not violated.

What is claimed is:

1. An eaves-trough hanger comprising a strap metal member having an elongated, substantially straight leg, a plurality of spaced-apart mounting apertures in said leg, a forwardly bent flange on the lower extremity of said leg, said flange being substantially at right angles with respect to said leg, an arm integrally connected to and forwardly extending from the upper extremity of said leg, said arm having an inverted U-shaped portion connected at its opposite ends to adjacent portions of said leg and arm respectively, said U-shaped portion being substantially compressed to provide a small vertical slot-

like space between said leg and said arm, a downwardly bent flange on the outer extremity of said arm; a retainer on said arm adjacent said outer extremity, said retainer comprising a wire bent to a substantially Z shape, one end of the Z being in the form of a U and the other end being offset to provide a shaft portion, said shaft portion passing through an aperture in said arm spaced a given distance back from said outer extremity whereby said retainer may be swung with respect to said arm, and a locking boss on the upper side of said arm adjacent the last-mentioned aperture and engageable by the middle portion of said retainer for holding said retainer in locking position.

2. An eaves-trough hanger comprising a strap metal member having an elongated, substantially straight leg, a plurality of spaced-apart mounting apertures in said leg, a forwardly bent flange on the lower extremity of said leg, said flange being substantially at right angles with respect to said leg, an arm forwardly extending from the upper extremity of said leg, a connector integrally connecting the adjacent ends of said arm and leg together, said connector being an inverted U-shaped portion of said strap metal member having one side which extends downwardly a given distance along the front side of said leg to provide a slot, a retainer on said arm adjacent said outer extremity, said retainer comprising a wire bent to a substantially Z shape, one end of the Z being in the form of a U and the other end being offset to provide a shaft portion, said shaft portion passing through an aperture in said arm spaced a given distance back from said outer extremity whereby said retainer may be swung with respect to said arm, and a locking boss on the upper side of said arm adjacent the last-mentioned aperture and engageable by the middle portion of said retainer for holding said retainer in locking position.

3. An eaves-trough hanger comprising a strap metal member having an elongated, substantially straight leg, a plurality of spaced-apart mounting apertures in said leg, a forwardly bent flange on the lower extremity of said leg, said flange being substantially at right angles with respect to said leg, an arm integrally connected to and forwardly extending from the upper extremity of said leg, said arm having an inverted U-shaped portion connected at its opposite ends to adjacent portions of said leg and arm respectively, said U-shaped portion being substantially compressed to provide a small vertical slot-like space between said leg and said arm, a downwardly bent flange on the outer extremity of said arm; a retainer on said arm adjacent said outer extremity, said retainer comprising a wire bent to a substantially Z shape, one end of the Z being in the form of a U and the other end being offset to provide a shaft portion, said shaft portion passing through an aperture in said arm spaced a given distance back from said outer extremity whereby said retainer may be swung with respect to said arm, and a locking boss on said arm adjacent the last-mentioned aperture and engageable by one portion of said retainer to hold said retainer in locking position.

4. An eaves-trough hanger comprising a strap metal member having an elongated, substantially straight leg, a plurality of spaced-apart mounting apertures in said leg, a forwardly bent flange on the lower extremity of said leg, said flange being substantially at right angles with respect to said leg, an arm integrally connected to and forwardly extending from the upper extremity of said leg, said arm having an inverted U-shaped portion connected at its opposite ends to adjacent portions of said leg and arm respectively, said U-shaped portion being substantially compressed to provide a small vertical slot-like space between said leg and said arm, said arm having an upwardly projecting reinforcing ridge whereby water falling on the upper surface of said arm will drain laterally there-off, a downwardly bent flange on the outer extremity of said arm; a retainer on said arm adjacent said outer extremity, said retainer comprising a wire bent to a substantially Z shape, one end of the Z being in

the form of a U and the other end being offset to provide a shaft portion, said shaft portion passing through an aperture in said arm spaced a given distance back from said outer extremity, whereby said retainer may be swung with respect to said arm, and a locking boss on the upper side of said arm adjacent the last-mentioned aperture and engageable by the middle portion of said retainer for holding said retainer in locking position.

5. An eaves-trough hanger comprising a strap metal member having an elongated, substantially straight leg, a forwardly bent flange on the lower extremity of said leg, said flange being substantially at right angles with respect to said leg, an arm integrally connected to and forwardly extending from the upper extremity of said leg, said arm having an inverted U-shaped portion connected at its opposite ends to adjacent portions of said leg and arm respectively, said U-shaped portion being substantially compressed to provide a small vertical slot-like space between said leg and said arm, a downwardly bent flange on the outer extremity of said arm; a retainer on said arm adjacent said outer extremity, said retainer comprising a wire bent to a substantially Z shape, one end of the Z being in the form of a U and the other end being offset to provide a shaft portion, said shaft portion passing through an aperture in said arm spaced a given distance back from said outer extremity whereby said retainer may be swung with respect to said arm.

6. An eaves-trough hanger comprising a strap metal member having an elongated, substantially straight leg

with a forwardly bent flange on its lower extremity for supporting the bottom of an eaves-trough, an arm integrally connected to and forwardly extending from the upper extremity of said leg and having a downwardly bent flange on the outer extremity thereof; and a retainer on said arm for engaging an upper rearwardly extending flange of an eaves-trough, said retainer being formed of wire and having two end portions integrally joined by an intermediate portion, one of said end portions passing loosely through an aperture in said arm adjacent said downwardly bent flange whereby said retainer is pivotally mounted for movement between a first eaves-trough flange-engaging position and a second disengaged position, one of said retainer end portions being bent to be disposed below said arm and to engage the underside of said eaves-trough flange in the first position of said retainer, the other of said retainer end portions being bent to be disposed above said arm and having a hook formed on its end for embracing said eaves-trough flange in the first position of said retainer.
